**COMBINED CAP AND FLEXIBLE BOTTLE FOR
DISPENSING LUBRICANTS OR THE LIKE**

David A. Clark, Atherton, Mo., assignor to Clark Manufacturing Company, Atherton, Mo., a partnership

Filed Feb. 23, 1960, Ser. No. 59,462

Term of patent 7 years

(Cl. D58—17)

Fig. 1.

Fig. 2.

Fig. 3.

FIG. 1 is a side elevational view of a combined cap and flexible bottle for dispensing lubricants or the like, showing my new design;

FIG. 2 is a front elevational view thereof; and

FIG. 3 is a top plan view thereof.

I claim:

The ornamental design for a combined cap and flexible bottle for dispensing lubricants or the like, as shown.
